MIXTURE CONTROL

Guy E. Beardsley, Jr., Hartford, and Wright A. Parkins, West Hartford, Conn., assignors, by mesne assignments, to United Aircraft Corporation, a corporation of Delaware

Application May 25, 1934, Serial No. 727,508

21 Claims. (Cl. 261—39)

This invention relates to mixture control mechanism and more particularly to mechanism for controlling the jets in carburetors in response to changes in atmospheric pressure.

5 In the operation of airplanes, powered by internal combustion engines it is necessary to adjust the air-fuel ratio in accordance with differences in atmospheric density. For instance, as the atmospheric pressure decreases it becomes 10 necessary to decrease the quantity of fuel delivered per unit volume of air. In engines fed by means of a carburetor, this may be done by closing one or more of a series of fuel jets so that the remaining jets deliver a smaller quantity 15 of fuel.

One of the objects of this invention is to provide means for controlling the fuel-air ratio of a combustible mixture.

Another object is to provide automatic means for controlling the jets of a carburetor.

20 Other objects and advantages will be apparent from the specification and the accompanying drawing which show what is now considered the preferred embodiment.

25 Fig. 1 is a somewhat diagrammatic view showing a carburetor partly in section, and showing the jet control mechanism.

Fig. 2 is a view similar to Fig. 1, showing another form of jet control mechanism.

30 Fig. 3 is a somewhat diagrammatic view showing the connection between the control jets and the main jet.

This invention has been shown in Figs. 1 and 35 3 as embodied in a carburetor having a body 10 and a discharge jet 12 located in the throat of a Venturi tube in an intake passage, not shown. The discharge jet is fed from a manifold 14 which, in turn, is fed from a plurality of control jets 16, 18, 20 and 24. Fuel is led into 40 the chambers above these jets by any suitable means such as conduits 26 and 28, from the float chamber 30 or any other suitable source of fuel.

In the modification shown in Fig. 1, jet 24 45 is always open and determines the minimum amount of fuel which can be fed to the main jet under full or wide open throttle conditions. The remaining jets 16, 18, and 20 may be closed by means of needle valves 32, 34, and 36 respectively. These valves are normally held off their seats by springs 38 but may be forced to closed position against the tension of the spring by the introduction of fluid under pressure into the chamber above the needle valve. Each valve 55 is provided with a plunger 40 to prevent the pas-

sage of fluid thereby and to act as a piston to force the valve to closed position.

The fluid for closing the needle valves is controlled by a piston valve 42 adapted to slide in a cylinder 44, and connect ports 46, 48, and 50 5 with either a source of fluid pressure or with a drain. Fluid pressure may be introduced through pipe 52 and pipes 54 and 56 may be connected with a drain. This then provides a balanced valve for operating the needle valves so that only the frictional forces must be overcome in the operation of the valve.

This piston valve 42 may be operated either by manual means or by a pressure responsive device such as the bellows 82 and its cooperating mechanism, detailed operation of which is described below. By the use of the bellows 82, the operation of the jets becomes automatic and depends only upon the pressure acting upon the bellows 82 and therefore acts to close the jets as the airplane climbs to higher altitudes and reduced pressures. Any suitable source of fluid pressure for actuating the jets may be used, such as the pressure oiling system of an internal combustion engine.

25 In the modification shown in Fig. 2, a different form of jet control is disclosed. In this modification, fuel is fed to the manifold 14 through the jets 59, 60, 62, 64, and 66, all of these jets being fed from a reservoir 68 which, in turn, is fed from the float chamber and by the conduit 28.

20 Jet 66 always remains open similar to the jet 24 of the modification shown in Fig. 1. The remaining jets may be closed by means of a piston 70 sliding in the chamber 68. This piston may be manually operated or, as shown, automatically operated by means of a pressure responsive bellows 82.

25 The jet control piston could be operated directly by bellows 82, but the form shown in Figs. 1 and 2 is preferred. The form of automatic operating mechanism shown in Fig. 2 is substantially the same as that shown in Fig. 1. This mechanism will, therefore, be described only 45 in connection with Fig. 2; its application to the structure of Fig. 1 will, it is believed, be apparent from this description and the showing of this figure. Referring to Fig. 2 the piston 70 is connected by means of a bar 74 with a fluid pressure actuated piston 72 mounted in a cylinder 14. The introduction of fluid into this cylinder is controlled by valves 76 and 78 connected to a common actuating arm 80. Pressure is introduced into the valve chamber through a pipe 82 50

and the other portions of the valve chamber are connected to a drain by means of the pipes 84 as will be evident from the drawing. Operation of the valves toward the right, as seen in Fig. 2, will introduce pressure into the right hand end of cylinder 74 and connect the left hand end thereof with the drain, thus moving the piston 72 and with it the piston 78 toward the left.

10 Operation of the valves 76 and 78 is controlled by means of a pressure responsive bellows 82 acting on lever arm 84 which, in turn, is connected with the valve actuating rod 80. A compression spring 86 is located between the piston 15 72 and the lever arm 84 and tends to move piston 72 towards the left as seen in Fig. 2, and tends to collapse the bellows 82 and to move the lever arm 84 toward the right as seen in Fig. 2. The bellows 82 may be a sealed bellows filled with a 20 suitable gas, such as air at sea level pressure under normal temperature, or it may be an evacuated bellows having a spring therein to prevent it from collapsing. By the inclusion of air or other gas in the bellows, it is made temperature responsive as well as pressure responsive. This bellows may be placed so as to be affected by atmospheric pressure, or it may be placed in the intake below the carburetor so as to be affected only by the pressure and temperature in that intake. The term "atmospheric pressure" as used in the following claims is intended to define pressure acting on the bellows under any of these conditions.

35 In the operation of this device, a reduction in the pressure surrounding the bellows 82 or an increase in the temperature affecting the bellows 82 will cause the bellows to expand and move the lever arm 84 toward the left, as seen in Fig. 2. This will cause the valves 16 and 78 to 40 put oil under pressure in the left hand end of chamber 74 and move the piston 72 towards the right. This, in turn, will compress spring 86 and thereby partially collapse bellows 82 which, in turn, will bring the lever arm 84 and valves 45 76 and 78 back to neutral position and thereby hold piston 72 in its changed position so that the bellows 82 will not be required to make more than slight movements to actuate the piston 72 its full stroke. Movement of the piston 72 toward 50 the right in response to a reduction in pressure in the bellows 82 will, of course, cause a movement of the piston 78 toward the right and act to close off one or more of the jets 58, 60, 62, and 64. By the correct proportioning of the 55 jets and the jet operating mechanism, it is possible to obtain a fuel air ratio that will have but a slight variation for the complete temperature and pressure range of the regulating device. This will then provide a means which will require no attention from the operator, and will maintain the combustible mixture substantially uniform from the ground up to an altitude corresponding to the pressure limits of the device 60 and through temperature ranges within the limits of the device.

Although this control mechanism has been shown in conjunction with specific mechanism, it is to be understood that the invention is not limited thereto and that the invention can be otherwise embodied and that the drawing is not to be construed as defining or limiting the scope of the invention, but as illustrative only. This invention may, therefore, be used in other ways and various changes may be made therein with-

out departing from the spirit and scope of the invention as defined by the following claims.

What we claim is:

1. In a carburetor having a fuel nozzle, means for controlling the flow of fluid through said nozzle comprising a plurality of normally open jets in the fuel line leading to said nozzle, means for selectively closing said jets comprising, a source of fluid pressure, plungers associated with the jets and adapted in one position to close them, and a valve for selectively connecting said plungers with said source of pressure to move said plungers to close said jets.

2. Means for controlling the quantity of fuel fed to a fuel mixing device, comprising a plurality of normally open jets in the fuel line leading to the fuel mixing device, plungers associated with said jets and adapted in one position to close them, resilient means for normally holding said plungers away from said jets to maintain the jets in open position, means for introducing fluid pressure to one side of said plungers to move them to close said jets and a valve actuated in accordance with variations in atmospheric pressure for selectively controlling the introduction of fluid to said plungers.

3. Means for controlling the quantity of fuel fed to a fuel mixing device comprising a conduit through which the fuel is led, jets in the side of said conduit, a plunger closing one end of said conduit and adapted to slide therein, said plunger adapted in one position to cover all but one of said jets and means for moving said plunger to uncover the other jets in accordance with increases in atmospheric pressure.

4. Means for controlling the quantity of fuel fed to a fuel mixing device comprising in combination a plurality of jets arranged in the fuel line leading to the mixing device, a plunger for controlling said jets, a fluid operated piston operatively connected with said plunger, a valve for controlling the fluid to operate said piston, an expandable bellows having a movable end, a spring arranged between the movable end of said bellows and said piston and adapted to be actuated by movement of said piston and a connection between the movable end of said bellows and said valve.

5. In a carburetor, mixture control means, comprising, in combination, means for regulating the flow of fuel, and means for operating said regulating means, said operating means comprising a pressure and temperature responsive device, a fluid pressure operated piston, a resilient connection between said piston and said device, a valve controlling the fluid to operate said piston, a connection between said valve and said device adapted to operate said valve in response to movements of said device, and a connection between said piston and said regulating means.

6. Means for operating a fuel regulating device, comprising, in combination, a pressure and temperature responsive mechanism, a fluid operated piston for moving said regulating device, a valve controlling the operating fluid for said piston for controlling the movements of said piston, a connection between said valve and said mechanism adapted to operate said valve and in consequence said piston in response to pressure and temperature changes, a resilient connection between said piston and said mechanism adapted upon movement of said piston to restore said mechanism to its original position.

7. In a carburetor, a jet controlling plunger, a piston for moving said plunger to control the

- jets, a pressure and temperature responsive device for controlling the position of said piston and said plunger and a resilient connection between said piston and said device adapted upon movement of the piston to impose forces on said device to oppose the movement that caused the movement of the piston and to bring the device to its original position.
8. In a carburetor, a jet controlling plunger, a piston connected therewith for moving said plunger to control the jets, a pressure and temperature responsive device for controlling the position of said piston in accordance with pressure and temperature conditions, a resilient connection between said piston and said device, said piston adapted to compress or expand said resilient connection in opposition to movements of said device.
9. In a carburetor, a jet controlling plunger, a fluid operated piston connected therewith for moving said plunger to control the jets, a valve controlling the operating fluid for said piston for controlling the movements of said piston, a pressure and temperature responsive device for controlling the position of said valve, said valve having a neutral position and having operative positions on either side of the neutral position, a resilient connection between said piston and said device, said piston adapted to compress or expand said resilient connection to bring the device and valve back to neutral position after each movement to an operative position.
10. In a carburetor, in combination, jet controlling means, a fluid pressure operated piston for operating said jet controlling means, a valve for controlling the operating fluid for said piston, a temperature and pressure responsive device, a connection between said device and said valve adapted to impart movement of said device to said valve, one position of said device adapted to place the valve in a neutral position and hold the piston stationary, a resilient connection between said piston and said device adapted to exert a variable force on said device in accordance with the position of said piston, said piston adapted to vary the force exerted by the resilient means to oppose the movement of the device which caused the movement of said piston.
11. In a carburetor, in combination, a fuel nozzle and means for regulating the flow of fuel to said nozzle in accordance with variations in atmospheric pressure, said regulating means comprising a pressure responsive device having a movable portion, a fluid pressure operated piston, means for controlling the operation of said piston connected to the movable portion of said pressure responsive device for movement therewith, whereby movement of said movable portion causes movement of said piston, a spring connecting said device and said piston whereby movement of said device to compress said spring causes movement of said piston to further compress said spring and return said movable portion to its original position, means for varying the effective size of the conduit leading to said nozzle to vary the flow of fuel thereto and a connection between said piston and said last mentioned means whereby movement of said piston will move said last mentioned means to vary the flow of fuel to said nozzle.
12. In a carburetor having a fuel nozzle fed by a plurality of fuel jets, means for controlling the quantity of fuel fed to said nozzle by said jets comprising a plurality of independent, fluid pressure operated, jet controlling plungers.
13. In a carburetor having a plurality of fuel jets, means for controlling the quantity of fuel fed by said jets comprising a plurality of independent, fluid pressure operated, jet controlling plungers and means controlled by atmospheric pressure for selectively operating said plungers at predetermined atmospheric pressures.
14. In a carburetor having a fuel nozzle, means for controlling the flow of fluid through said nozzle comprising a plurality of normally open jets in the fuel line leading to said nozzle, fluid pressure operated means for individually closing said jets and a valve for selectively connecting said last named means with a source of fluid pressure.
15. Means for controlling the quantity of fuel fed to a fuel mixing device comprising a fuel line leading to said fuel mixing device, a plurality of fuel metering jets arranged in said fuel line, means for closing said jets and fluid pressure operated means for selectively operating said closing means and means responsive to atmospheric pressure for controlling said fluid pressure operated means, to vary the quantity of fuel delivered per unit volume of air.
16. In a carburetor, means for regulating the fuel air ratio of the carburetted mixture, comprising a plurality of fixed fuel jets and means for selectively controlling said jets, a piston for moving said controlling means, a pressure responsive device for controlling the position of said piston and said controlling means and a resilient connection between said piston and said device adapted upon movement of the piston to impose forces on said device to oppose the movement that caused the movement of the piston and to bring the device to its original position.
17. In a carburetor, jet controlling means, a piston for moving said means to control the jets, an expansible chamber device for controlling the position of said piston and said means, means for moving said piston upon movement of said expansible chamber device, and a resilient connection between the piston and said device adapted upon movement of the piston to restore said device to its original position.
18. In a carburetor having a fuel nozzle, means for controlling the flow of fluid through said nozzle, comprising a plurality of jets in the fuel line leading to said nozzle, said jets adapted to be selectively opened and closed, a piston valve associated with said jets and adapted to control the opening and closing of said jets and means responsive to atmospheric pressure for moving said piston valve to control said opening and closing.
19. In a carburetor of the float chamber type, a fuel nozzle, means for regulating the quantity of fuel delivered by said nozzle per unit volume of air passing said nozzle to thereby regulate the fuel-air ratio of the carbureted mixture, said regulating means comprising, a plurality of fuel metering jets in the fuel line leading to said nozzle, a piston valve for controlling the opening and closing of said jets, and means responsive to atmospheric pressure for controlling said piston valve to selectively close said jets upon decreases in atmospheric pressure.
20. In a carburetor having a fuel nozzle, means for controlling the flow of fuel through said nozzle in accordance with atmospheric pressure, comprising, a plurality of jets in the fuel line leading to said nozzle, a piston valve for selectively closing said jets and means responsive to changes in atmospheric pressure for operating said piston

valve to selectively close said jets upon decreases in the atmospheric pressure.

21. In a carburetor, means for regulating the fuel-air ratio of the carbureted mixture by regulating the quantity of fuel delivered per unit volume of air, said regulating means comprising a plurality of fixed fuel jets, a nozzle fed by said jets and means for selectively opening or closing

said jets, said last named means comprising a piston valve associated with said jets and means responsive to atmospheric pressure for moving said piston valve to control said opening and closing.
